DESIGN FOR A FLY SWATTER

John L. Bennett and Stephen A. Platt, Decatur,
Ill., assignors to U. S. Manufacturing Corpora-
tion, Decatur, Ill., a corporation of Illinois

Application February 3, 1934, Serial No. 50,607

Term of patent 14 years

To all whom it may concern:

Be it known that we, JOHN L. BENNETT and STEPHEN A. PLATT, citizens of the United States, and residents of Decatur, county of Macon, and State of Illinois, have invented a new, original, and ornamental Design for a Fly Swatter, of which the following is a specification, reference being had to the accompanying drawing, forming part thereof.

In the drawing—

Figure 1 is a face elevation of a fly swatter embodying our design.

Figure 2 is a side elevation of the fly swatter shown in Figure 1.

We claim:

The ornamental design for a fly swatter as shown.

JOHN L. BENNETT.
STEPHEN A. PLATT.
